Primary Examiner — Sandra Snapp*Assistant Examiner* — Holly E. Thurman(74) *Attorney, Agent, or Firm* — Kilpatrick Townsend & Stockton LLP(57) **CLAIM**

The ornamental design for a keyboard layout for a protective folio, as shown and described.

DESCRIPTION

FIG. 1 is a perspective view of a first embodiment of a keyboard layout for a protective folio showing our new design;

FIG. 2 is a top plan view thereof;

FIG. 3 is a perspective view of a second embodiment of a keyboard layout for protective folio, shown our new design; and,

FIG. 4 is a top plan view thereof.

The broken lines shown represent unclaimed subject matter and form no part of the claimed design.

1 Claim, 4 Drawing Sheets(56)
